[57] CLAIM

The ornamental design for goniometer frame, as shown and described.

DESCRIPTION

FIG. 1 shows an isometric view of the preferred embodiment of the design of the present invention, with environment shown in dashed lines.

FIG. 2 is a top plan view of the preferred embodiment of the design of the present invention, with environment shown in dashed lines.

FIG. 3 is a fragmentary view of a second, alternate embodiment of the design of the present invention.

FIG. 4 is a fragmentary view of a third, alternate embodiment of the design of the present invention.

FIG. 5 is a left-side elevation of the preferred embodiment of the design of the present invention, with environment shown in dashed lines.

FIG. 6 is a bottom plan view of the preferred embodiment of the design of the present invention, with environment shown in dashed lines.

FIG. 7 is a front elevation of the preferred embodiment of the design of the present invention, with environment shown in dashed lines.

FIG. 8 is a rear elevation of the preferred embodiment of the design of the present invention, with environment shown in dashed lines; and,

FIG. 9 is a right-side elevation of the preferred embodiment of the design of the present invention, with the environment shown in dashed lines.
